CIRCUIT INTERRUPTER

Bernhard Ulrich, Jr., and Philip Ulrich,
Corpus Christi, Tex.

Application July 14, 1952, Serial No. 298,874

8 Claims. (Cl. 200—32)

1

This invention relates to a circuit interrupter and particularly to an interrupter for periodically interrupting a circuit at predetermined intervals.

In certain applications it is desirable to have an intermittent application of potential to a load circuit and in other circuits it is desirable to reduce the total effective voltage of current applied to a load over a predetermined interval.

In special circumstances it is sometimes desirable to pick out one polarity of an alternating current circuit to apply unidirectional current to a load.

The present invention provides a device for periodically interrupting a circuit and for controlling the length and frequency with which the circuit is interrupted.

This is accomplished by means of a mercury switch consisting of a chamber having an insulating partition therein and an aperture in the partition and means for controlling the extent and periodicity of a current connection through the aperture.

It is accordingly an object of the invention to provide an improved circuit interrupter.

It is a further object of the invention to provide an interrupter having substantially arcless interruptions.

It is a further object of the invention to provide an interrupter having a non-burning separable contact.

It is a further object of the invention to provide a circuit interrupter the extent of the interruption of which can be controlled.

It is a further object of the invention to provide an improved mercury switch.

It is a further object of the invention to provide a cam controlled rotary circuit interrupter.

It is a further object of the invention to provide an improved contactor for supplying current to a rotary switch.

Other objects and many of the attendant advantages of the present invention will be apparent from the following detailed description taken in conjunction with the accompanying drawings, in which:

Figure 1 is an elevational view of a circuit interrupter according to the invention;

Figure 2 is an enlarged sectional elevational view taken substantially on the plane indicated by the line 2—2 of Figure 1;

Figure 3 is a cross section through the interrupter taken substantially on the plane indicated by the line 3—3 of Figure 2;

Figure 4 is a cross section taken substantially on the plane indicated by the line 4—4 of Figure 2;

Figure 5 is a fragmentary section taken on the plane indicated by the line 5—5 of Figure 4;

Figure 6 is a partial view substantially similar to Figure 6.

2

to Figure 2 but showing the interrupter in closed position;

Figure 7 is a partial cross section taken substantially on the plane indicated by the line 7—7 in Figure 6 and showing the internal arrangement of the interrupting chamber; and

Figure 8 is an exploded view of a cam member for controlling the interrupter.

In the embodiment according to the invention a housing 10 is mounted on a suitable base 12 and has an operating motor 14 rigidly secured therein by suitable means such as screws 16. An operating shaft 18 extends substantially axially in the housing 10. A U-shaped frame member 20 has a yoke 22 which has an aperture 24 receiving the shaft 18 which is provided with a flat surface 26 for receiving a set screw 28 for locking the yoke 22 on the shaft 18.

A transverse U-shaped member having legs 30 and 32 is mounted at the top end of the U-shaped frame 20 preferably integrally connected thereto.

The U-shaped body having the legs 30 and 32 is provided adjacent the ends of legs 32 with apertures 34 and 36 in which is mounted insulating bushings 38 and 40. A chamber 42 is substantially cylindrical in cross section and is provided with a closure 44 which encloses an insulating lining 46. The sides of the chamber 42 are provided with an insulating lining 48 which in turn is provided with an insulating partition 50 so that the chamber 42 is divided into two substantially equal parts. Mercury pools 52 and 54 are provided in the sub-chambers provided by

30 the partition 50 and one of the sides 56 of the chamber 42 is in electrical contact with one of the pools such as the pool 54. A terminal member 58 is in contact with one side and the periphery of the pool 52 and has extending therefrom

35 a stub shaft 60 which extends through the insulating liner 46 and the insulating bushing 38 to journal the chamber 42 in the leg 30 while a conducting screw 62 is screwed into contact with the wall 56 and extends through the bushing 38 to provide a bearing for the chamber 42 in the leg 32. A counterweight 64 is mounted on the opposite ends of the legs 30 and 32 by means of a rivet or other suitable fastener 66. An electrical conductor 68 is connected to the stub

40 shaft 60 while an electrical conductor 70 is connected to the housing 42.

45 A stud 74 extends from the surface of the chamber 42 and has a resilient element 76 connected thereto by means of a bushing 78 and extending between the bushing 78 and the counterweight 64. A cam follower support member 80 extends upwardly from the housing 42 and has mounted on the top thereof a cam follower 82.

50 A cam guide 84 is mounted in the top of the housing 10 and has slidably mounted therein a

55

cam shaft 86. A guide 84 is provided with a vertical slot 88 and the cam shaft 86 is provided with a pin 90 which extends outwardly through the vertical slot 88. An actuating disk 92 is provided with a sleeve 94 which surrounds the guide 84 and has a spiral slot 96 therein also receiving the end of the pin 90. The sleeve 94 being rotatable around the guide 84 for causing reciprocation of the cam shaft 86.

A substantially cylindrical cam head 98 is provided on the end of the cam shaft 86 and an axial aperture 100 receives a pin 102 the lower end of which is provided with a cam 104. A cam element 106 and a cam element 108 are non-rotatably mounted on the pin 102 which extends into the aperture 100 to produce a cam element for cooperation with a cam follower 82. The resilient spring 76 pulls the chamber 42 so that it rotates about the axle produced by the stub shaft 60 and the screw 62 so that the cam follower 82 is forcibly retained against the cam surface of the various cam elements.

The pools 52 and 54 are constituted of electrical conducting liquid and preferably mercury which are maintained in separated positions by means of the partition 50. The axis defined by the stub shafts 60 and the screw 62 is offset laterally from the axis of rotation defined by the shaft 18 so that when the motor 14 is operative to rotate the chamber, the liquid material will be thrown to the outside to transfer the pools in each of the chambers to the lateral or side portions of the chambers. The partition 50 is provided with an aperture 110 in the inner upper quadrant thereof. Preferably the aperture 110 is substantially quadrant shaped and is so positioned that when the interrupter is at rest the pools 52 and 54 will be so related to the aperture that the surface of the pool will be lower than the edge 112 of the aperture and so related that when the chamber is being rotated the surface of the pools 52 and 54 will be substantially parallel and separated from the edge 114 when the edge 114 is substantially vertical. The conductors 118 and 120 supply current to the motor 14 and also to the brushes 122 and 124. The brushes 122 and 124 are mounted in opposite ends of an insulating block 126 by means of insulating bushings 128 and 130 which are secured in the block 126 by means of the pin 132 which is screwed into an aperture 134 in the casing of the motor 14. A connection from the brushes 122 and 124 to the terminals 60 and 56 is provided by means of an insulating disk 140 on which are mounted annular conductors 142 and 144. Brush 122 being in contact with the annular conductor 142 and the brush 124 being in contact with the annular conductor 144. The annular conductor 144 is provided with a pair of extensions 146 and 148 which extend through apertures in the disk 140 and are bent to fasten the annular member 144 against the under surface of the insulating disk 140. The electrical conductor 170 extending from the casing 42 is electrically connected to the extension 146 so that the annular conductor 144 is electrically connected to the housing 42 and the terminal 56. The conductor 68 is likewise conductively connected to the annular member 142 so that the brush 122 is electrically connected to the terminal 58 and to the conducting material in the pool 52.

In the operation of the circuit interrupter according to the invention the cam member 104 is preferably substantially cylindrical in formation

and of such size that the cam follower 82 while operating thereon will maintain the edge 114 in substantially vertical relation so that the pools 52 and 54 will be electrically insulated from each other and the circuit therethrough will be interrupted. When it is desired to cause periodic impulses of current through the device the member 94 is rotated by means of the disk 92 so that the cam shaft 86 is protruded downwardly so that the cam follower 82 will ride on the surface of the cam member 106. This will cause the cam follower 82 to follow an eccentric path about the cam shaft 86. When the cam follower 82 is on the outside of the cam 106 as shown in Figure 6 the chamber 42 will be so far rotated that the edge 114 of the aperture 110 will be so far inclined as to be immersed in the liquid of the two pools so that the two pools will be in contact and an electrical current will flow through the interrupter. When the cam follower 82 is on the lower part of cam 106 there will be short impulses of current with relatively large intervals of no current. At the top of cam 106 the on and off intervals are equal.

When the cam follower 82 is on the cam 108 the proportion of on and off periods will be changed so that at the bottom of the cam 108 the on period will exceed the off period until at the top of the cam 108 the on period will be continuous so that when the cam follower 82 is following the cylindrical member 98 there will be no off period.

When the device is at the top of cam 108 and is rotating at 3600 R. P. M. and 60 cycle current is applied thereto, by merely synchronizing the rotor with the alternations of the supply circuit the device will supply potential of a single polarity and completely eliminate the potential of the other polarity so that the device becomes in effect a single pole rectifier.

It will thus be seen that the present invention provides a circuit interrupter which will provide any particular desired proportion of a full wave or may if desired selectively apply only one-half wave of a full wave to produce a rectified current.

The present interrupter can thus be utilized for controlling the potential applied to any load from zero to full potential.

It will thus be seen that the device will supply current from a small minority of the full cycle to substantially half the full cycle and then substantially to the full cycle as may be desired. It is possible to utilize the half full wave time as a rectifier by synchronizing the rotor with the impulses supplied thereto.

In the illustrated embodiment of the invention a preferred embodiment has been disclosed and described according to the best present understanding thereof. It will be apparent to those skilled in the art that changes and modifications can be made therein without departing from the spirit of the invention.

Having described the invention, what is claimed as new is:

1. A periodic circuit interrupter comprising a casing, a frame mounted in said casing for rotation about a vertical axis in said casing, power means operatively connected in driving relation to said frame, a cylindrical chamber mounted on said frame, the axis of said chamber being transverse to the axis of said frame, said chamber being disposed laterally of the axis of said frame, two pools of conducting liquid in said chamber, an insulating partition between said

pools, an aperture in the upper inner portion of said partition, the bottom of said aperture being above the at rest level of said pools, the side of said aperture being above the level of said pools when said frame is rotating and said side is substantially vertical, means for cyclically oscillating said chamber about its axis in unison with the rotation of said frame about its axis.

2. A periodic circuit interrupter comprising a casing, a frame mounted in said casing for rotation about a vertical axis in said casing, power means operatively connected in driving relation to said frame, a cylindrical chamber mounted on said frame, the axis of said chamber being transverse to the axis of said frame, said chamber being disposed laterally of the axis of said frame, two pools of conducting liquid in said chamber, an insulating partition between said pools, an aperture in the upper inner portion of said partition, the bottom of said aperture being above the at rest level of said pools, the side of said aperture being above the level of said pools when said frame is rotating and said side is substantially vertical, means for cyclically oscillating said chamber about its axis in unison with the rotation of said frame about its axis, a pair of slip rings mounted on said frame, conductors extending between the respective slip rings and the opposed pools, brush means connecting an electric circuit to said slip rings.

3. A periodic circuit interrupter comprising a casing, a frame mounted in said casing for rotation about a vertical axis in said casing, power means operatively connected in driving relation to said frame, a cylindrical chamber mounted on said frame, the axis of said chamber being transverse to the axis of said frame, said chamber being disposed laterally of the axis of said frame, two pools of conducting liquid in said chamber, an insulating partition between said pools, an aperture in the upper inner portion of said partition, the bottom of said aperture being above the at rest level of said pools, the side of said aperture being above the level of said pools when said frame is rotating and said side is substantially vertical, a cam member mounted substantially axially of said casing, a cam follower mounted on said housing, resilient means yieldingly urging said cam follower against said cam member.

4. A periodic circuit interrupter comprising a casing, a frame mounted in said casing for rotation about a vertical axis in said casing, power means operatively connected in driving relation to said frame, a cylindrical chamber mounted on said frame, the axis of said chamber being transverse to the axis of said frame, said chamber being disposed laterally of the axis of said frame, two pools of conducting liquid in said chamber, an insulating partition between said pools, an aperture in the upper inner portion of said partition, the bottom of said aperture being above the at rest level of said pools, the side of said aperture being above the level of said pools when said frame is rotating and said side is substantially vertical, a cam member mounted substantially axially of said casing, a cam follower mounted on said housing, resilient means yieldingly urging said cam follower against said cam member, a plurality of cam surfaces on said cam member, means for selectively positioning said cam surfaces in contact with said cam follower.

5. A periodic circuit interrupter comprising a casing, a frame mounted in said casing for rotation about a vertical axis in said casing, power means operatively connected in driving relation

6 to said frame, a cylindrical chamber mounted on said frame, the axis of said chamber being transverse to the axis of said frame, said chamber being disposed laterally of the axis of said frame, two pools of conducting liquid in said chamber, an insulating partition between said pools, an aperture in the upper inner portion of said partition, the bottom of said aperture being above the at rest level of said pools, the side of said aperture being above the level of said pools when said frame is rotating and said side is substantially vertical, a cam member mounted substantially axially of said casing, a cam follower mounted on said housing, resilient means yieldingly urging said cam follower against said cam member, a counterweight mounted on said frame.

6. A periodic circuit interrupter comprising a casing, a frame mounted in said casing for rotation about a vertical axis in said casing, power means operatively connected in driving relation to said frame, a cylindrical chamber mounted on said frame, the axis of said chamber being transverse to the axis of said frame, said chamber being disposed laterally of the axis of said frame, two pools of conducting liquid in said chamber, an insulating partition between said pools, an aperture in the upper inner portion of said partition, the bottom of said aperture being above the at rest level of said pools, the side of said aperture being above the level of said pools when said frame is rotating and said side is substantially vertical, a cam member mounted substantially axially of said casing, a cam follower mounted on said housing, resilient means yieldingly urging said cam follower against said cam member, a counterweight mounted on said frame.

7. A periodic circuit interrupter comprising a casing, a frame mounted in said casing for rotation about a vertical axis in said casing, power means operatively connected in driving relation to said frame, a cylindrical chamber mounted on said frame, the axis of said chamber being transverse to the axis of said frame, said chamber being disposed laterally of the axis of said frame, two pools of conducting liquid in said chamber, an insulating partition between said pools, an aperture in the upper inner portion of said partition, the bottom of said aperture being above the at rest level of said pools, the side of said aperture being above the level of said pools when said frame is rotating and said side is substantially vertical, a cam member mounted substantially axially of said casing, a cam follower mounted on said housing, resilient means yieldingly urging said cam follower against said cam member, a counterweight mounted on said frame.

7. A circuit interrupter comprising a regular chamber, an insulating partition in said chamber, mercury pools in each side of said partition, electrical connections to each of said pools, said partition having an aperture therein, said aperture being spaced from said pools when said chamber is at rest, means for rotating said chamber about a vertical axis eccentric to said chamber, and means for varying the inclination of said chamber with respect to said vertical axis to determine the relation of said aperture to said pools.

8. A centrifugal circuit interrupter comprising a frame, an insulating chamber mounted on said frame, means for rotating said frame about an axis eccentric to said chamber, an insulating partition in said chamber and arranged radially to said axis, mercury pools in said chamber and separated by said partition, electrical circuit connections to said pools, said partition having an aperture therein, a cam device operative to vary the angular relation of said chamber to said axis whereby the relation of said aperture to said pools is varied.

BERNHARD ULRICH, JR.
